[57] CLAIM

The ornamental design for a fluorescent light adapter module, as shown and described.

DESCRIPTION

FIG. 1 is an exploded perspective view of a fluorescent light adaptor module showing my new design, with the broken line showing for illustrative purposes only and forming no part of the claimed design;

FIG. 2 is a side elevational view thereof, with the opposite side being a mirror image;

FIG. 3 is a top plan view of the adapter thereof, omitted for clarity of illustration only;

FIG. 4 is a side elevational view thereof, with the opposite side being a mirror image;

FIG. 5 is a bottom plan view thereof;

FIG. 6 is a bottom plan view of the electrical connector thereof, with the adaptor omitted for clarity of illustration only; and,

FIG. 7 is a bottom plan view of the adapter thereof.
